MOTORS

Eugene E. Sobeck and Jack M. Andresen, Winona, Minn., assignors to Lake Center Switch Company, Winona, Minn., a corporation of Minnesota

Filed May 14, 1963, Ser. No. 280,369

3 Claims. (Cl. 91—421)

This invention relates to motors and more particularly to stored energy type hydraulically damped motors.

A typical motor of this type may include a spring loaded piston assembly which, when released from a "cocked" position, moves against a hydraulic medium. The hydraulic medium is released gradually by controlled metering to limit movement of the piston assembly to a relatively slow uniform rate.

In contrast to the slow movement generally required during the motoring cycle, it is desirable that the piston assembly be capable of being moved to the "cocked" position very quickly.

One common motor of this type includes a cylinder having hydraulic fluid confined between a pair of spaced apart but connected spring loaded pistons. A metering hub or wall with appropriate ducts and valves is positioned between the pistons and regulates the discharge of the fluid from one side to the other thereof depending on the direction of movement of the pistons. This metering hub thus regulates fluid discharge and the speed at which the "cocked" spring may move the pistons to the "uncocked" position.

In making cylinders of this type difficulty has been encountered in economically sealing the metering wall within the cylinder as well as providing a check valve of high reliability and durability.

It is therefore a primary object of the invention to provide a novel check valve system which allows the hydraulic fluid to be relieved quickly during movement of the driven member to the "cocked" position but provides a positive leak proof seal when the driven member is being motored.

A further object of the invention is to provide a motor having a check valve system which is simple, inexpensive and extremely reliable over extended heavy duty cycling.

A still further object of the invention is to provide a combination check valve and metering hub sealing member.

Other objects of the invention will become apparent from the detailed specification to follow.

In the drawings:

FIG. 1 is a longitudinal sectional view of a motor of the invention showing it in the "cocked" position with the spring compressed.

FIG. 2 is a longitudinal sectional view showing the motor at the completion of its stroke or in the "uncocked" position.

FIG. 3 is an enlarged fragmentary sectional view of the check valve and sealing member of the motor showing the valve in the closed position during the "cocked" and motoring cycle.

FIG. 4 is a view similar to FIG. 3 but showing the check valve in the open position while the motor is being moved to the "cocked" position, and

FIG. 5 is a transverse sectional view showing an end view of the check valve and sealing member partially cut away.

With specific reference now to FIG. 1, the motor of the invention indicated at 10 includes a cylinder housing 11 and a piston assembly 12. The piston assembly 12 comprises a first piston 13 and a second piston 14 spaced apart and mounted on a piston rod 15. Both pistons 13

2

and 14 fit with minimum sliding clearance in the cylinder 11 and carry O-ring rubber seals 16.

The piston rod 15 is guided in the cylinder by a stationary cylindrical metering hub or wall 17 having a guiding bore 18 therein. The hub 17 is positioned between the pistons 13 and 14 and fixedly held by annular stake marks 19 in the cylinder wall 11 which seat in a mating groove of the hub.

A spring 29 engages the end of the piston 13 and urges the piston assembly 12 from the cocked position of FIG. 1 towards the left, and to the uncocked position shown in FIG. 2. Tabs 21 struck near one end of the cylinder retain the spring in the cylinder.

Initially the piston assembly 12 is held in the cocked position by a latch not shown which may engage a groove in rotatable connector 22. Such connector has a bore 23 therein the bottom of which is engaged by the piston rod 15 when the piston assembly is being moved toward the uncocked position or when being moved toward the cocked position. Flange 24 bent on the end of the cylinder retains the connector in the cylinder by engaging a turned rim 25 on the connector.

To control and limit fast movement of the piston assembly when it is being motored, hydraulic fluid 27 is confined in the cylinder between the two pistons 13 and 14, the seal being made by the O-rings 16. Since the metering hub 17 is between the pistons 13 and 14, the fluid is actually contained in two separate chambers 28 and 29 which vary in size depending on the location of the pistons with respect to the metering hub.

For passage of hydraulic fluid through the metering hub there is provided a duct 30 communicating between chambers 28 and 29. Fluid may also pass along the clearance provided between the hub and the piston as the bore 18 is intentionally slightly oversize as shown in FIGS. 3-5.

In use it is desirable for the piston assembly 12 to be able to move from the uncocked position shown in FIG. 2 to the cocked position of FIG. 1 as quickly as possible. On the other hand, in moving from the cocked to the uncocked position of FIG. 2, it is desirable that the spring action be damped and the piston assembly move at a slow controlled rate.

To accomplish this there is provided a novel valve and seal system indicated generally at 31 in combination with the metering hub 17. Particularly, the valve 31 is made of a resilient pliable material such as rubber and formed somewhat in the shape of an annular cap or tire having a top 32, a sleeve or annular wall 33 and an inwardly directed annular rib 34 along the side opposite said top. The cap top 32 has a circular opening 35 therein through which the piston rod 15 may pass.

Valve 31 is retained in position by the annular rib 34 which snaps into a mating groove of the metering hub 17. The hub is also turned to a reduced diameter to fit the inside of the valve cap as indicated at 36, FIG. 3. The outside diameter of the valve wall 33 when snapped over the hub is larger than the inside diameter of the cylinder 11. Thus when the hub is inserted in the cylinder, wall 33 compresses tightly against the inside of the cylinder thereby forming a seal. This is extremely important since it has been found very difficult to achieve adequate sealing of the hub by metal staking or swaging operations alone.

Toward the piston 13, the valve cap top 32 extends downwardly over the end of the metering hub a sufficient distance to overlap the duct 30. When hydraulic fluid is forced from the chamber 29 through the duct 30 in the direction Y (FIG. 4) by the piston 14 as the piston assembly is being moved toward the right and to the cocked position of FIG. 1, the valve top 32 will swing or bow

outwardly as shown at 37 in FIG. 4. This allow fluid to pass quickly from chamber 29 to chamber 28.

Some fluid will also pass along the clearance between the piston rod 15 and the bore 18 in the metering hub 17 in the direction Y.

Upon full movement to the cocked position of FIG. 1, the piston assembly 12 is held by the latching mechanism not shown which may be in engagement with the connector 22. At such position flow of hydraulic fluid back through duct 39 to chamber 29 is prevented by the valve cap top 32 which acts as a check valve. As shown in FIG. 3, the fluid 27 firmly presses the top 32 against the flat face 38 of the hub and in tight sealing engagement over the duct. The fluid in the two chambers is thus in substantial equilibrium.

When the piston assembly is unlatched, the spring 20 forces against the piston 13. Movement of the piston 13 exerts pressure on fluid 27 in chamber 28. Such pressure exerts additional pressure on the top 32 of the valve cap thereby assuring a tight seal over duct 30.

With duct 39 sealed tightly, the only place the fluid can pass to the chamber 29 is through the clearance afforded between piston rod 15 and hub bore 18 as shown by the arrows X. This restriction acts as a metering valve and restrains fast movement or motoring of the spring and piston rod. Movement of the piston rod is thus at a controlled uniform rate.

Since the valve top 32 has a closed loop circular opening 35 therein it does not have loose corners or flaps under which fluid may pass and thereby provides an extraordinarily good seal. Moreover, greater strength and durability are achieved since gradual weakening and tearing of the seal along corners or flap areas is eliminated.

While one embodiment of the invention has been shown, it will be appreciated that it may take other forms without departing from the spirit of the following claims.

What we claim is:

1. A motor including a tubular cylinder, a metering hub fixed within said cylinder and having an axial guide bore therein and a duct therein, a piston rod slideable in said bore, pistons fixed on said piston rod on opposite

5 sides of said metering hub and spaced a distance greater than the axial width of said metering hub, a valving member carried by said metering hub, said valving member having an annular wall surrounding a portion of said metering hub and located between said hub and said cylinder, said valve also having a top with an opening therein through which said piston rod may pass, said top extending toward the axial center of said cylinder and overlapping said duct in said hub.

10 2. In a motor having a metering hub sealed within a chamber for controlling passage of fluid therewith, said metering hub having a duct therein extending from one side to the other thereof, a valve carried by said metering hub, said valve having a sleeve portion extending axially along an outer portion of said metering hub and in contact with said chamber for sealing said metering hub with respect to said chamber, said valve also having a depending top at substantially right angles to said sleeve portion with an opening therein, said top being flexible to seal said duct in said metering hub when fluid moves in one direction and being resiliently moveable to allow fluid to pass through said duct when fluid is placed under pressure in the opposite direction.

15 3. A structure as claimed above in claim 2 wherein said sleeve has a rib extending downwardly toward the axial center of said hub and spaced apart from said top to form a locking ring in conjunction with a mating annular groove in said hub.
